UNITED STATES PATENT OFFICE.

CHARLES S. HEMPSTEAD, OF MASONTOWN, PENNSYLVANIA, ASSIGNOR TO HIMSELF AND ISAAC P. KENDALL, OF SAME PLACE.

COWL.

SPECIFICATION forming part of Letters Patent No. 254,314, dated February 28, 1882.

Application filed October 29, 1881. (Model.)

To all whom it may concern:

Be it known that I, CHARLES S. HEMPSTEAD, of Masontown, in the county of Fayette and State of Pennsylvania, have invented a new and useful Improvement in Cowls, of which the following is a full, clear, and exact description.

The object of the invention is to support a reversible cowl over a chimney by means substantially as described and claimed hereinafter.

Reference is to be had to the accompanying drawings, forming part of this specification, in which similar letters of reference indicate corresponding parts in both the figures.

Figure 1 is a sectional elevation of my improved cowl, taken on the line *x x* of Fig. 2. Fig. 2 is a sectional elevation taken on the line *y y* of Fig. 1.

A represents the vane, *B* the cowl proper, and *C* the chimney-cap, which has an ornamental outline, and is formed with the circular collar *c* and the right-angled flanges *b* and *b'*, the flange *b* being adapted to rest upon the top of the chimney, the flange *b'* being adapted to surround the chimney on the outside, as shown in the drawings. Secured to the under side of the flange *b* by means of the bolts *a a* is the downwardly-bent bar *D*, which extends down into the chimney when the cowl is in place, and secured upon the horizontal portion *e* of this bar, by means of the screw *d*, is the horizontal cross-bar *E*, which is formed with the upturned ends *i i*, through which the set-screws *f f* pass.

Upon the upper side of the flange *b*, and secured by the same bolts, *a a*, which secure the ends of the bar *D*, is placed the upwardly-bent bar *F*, which is perforated in the center and forms the journal of the vertical spindle *H*.

The lower end of this spindle is pointed and rests in a socket formed in the upper end of the bolt *d*, and the upper end of the spindle extends a short distance above the collar *c* of the chimney-cap, where it is reduced in size and forms the pivot for the vane-arm *g*. Upon the vane-arm *g* is placed the collar *J*, which surrounds the collar *c*, as shown, and turns with the vane. The cowl *B* is mounted on the upper edge of the collar *J*, and is secured thereto by the clasped or rolled joint *a'* in such manner that the cowl is adapted to be turned upon the collar for setting the cowl so that its opening will be toward or from the vane, as desired.

Upon the inside of the chimney are placed the plates *h h*, (shown in Fig. 2,) against which the points of the set-screws *f f* are turned for securing the cowl in and upon the chimney.

Having thus described my invention, I claim as new and desire to secure by Letters Patent—

1. The combination, with the collar *C*, having flanges *b b'* to hold it to the top of chimney, of the bars *D F*, provided with end flanges secured by bolts *a a* to opposite sides of the flanges *b*, as shown and described.

2. The cross-piece *E* and the bar *D*, secured together by the socketed screw *d*, in combination with the spindle *H*, cross-bar *F*, and the vane-arm, substantially as and for the purposes set forth.

3. In combination with the cross-bar *D*, carrying the cross-piece *E*, provided with the set-screws *f f*, the plates *h h*, substantially as and for the purposes set forth.

CHARLES S. HEMPSTEAD.
